UNITED STATES PATENT OFFICE.

LOUIS PLESHE, OF CHICAGO, ILLINOIS.

RAIL-JOINT.

1,395,136.

Specification of Letters Patent.

Patented Oct. 25, 1921.

Application filed February 1, 1921. Serial No. 441,668.

To all whom it may concern:

Be it known that I, LOUIS PLESHE, a citizen of the United States, residing at Chicago, in the county of Cook and State of Illinois, have invented new and useful Improvements in Rail-Joints, of which the following is a specification.

This invention relates to railway rail joints and an object of the invention is to provide a joint for railway rails which will prevent the sinking of the meeting ends of the rails, prevent lateral spreading movement and one which is designed to bring pressure to bear upon the rails, laterally and vertically in both up and down directions upon the base of the rails to securely and firmly hold the rails against any relative movement.

Other objects of the invention will appear in the following detailed description and in the accompanying drawings wherein:

Figure 1 is a top plan of the improved rail joint.

Fig. 2 is a perspective view of the rail joint.

Fig. 3 is a perspective view of the rail joint showing the side opposite to that illustrated in Fig. 2.

Fig. 4 is a cross section through the rail joint taken on the line 4—4 of Fig. 1.

Fig. 5 is a detailed perspective of one of the clamping plates of the rail joint.

Fig. 6 is a detailed perspective of the other clamping plate of the rail joint.

Fig. 7 is a detailed side elevation of a clamping washer used in the rail joint.

Referring more particularly to the drawings, the improved rail clamp comprises clamping plates 1 and 2, one of which is positioned upon each side of the webs 3 of ordinary T rails 4 at their meeting ends, as clearly shown in Fig. 1 of the drawing. These clamping plates 1 and 2 are provided with upwardly facing slightly inclined upper edges 5 which engage against the under surface of the heads 6 of the rails 4 while their base flanges 7 are shaped to snugly abut the upper surfaces of the bases 8 of the rails 4. Clamping plates 1 and 2 are securely clamped in engagement with the rails 4 by bolts 9 which extend transversely through the webs 3 of the rails and through the clamping plates 1 and 2. As the nuts 10 are tightened upon the threaded ends of the bolts 9, the clamping plates 1 and 2 will be drawn toward each other and conse-

quently toward the webs 3 of the rails, thereby applying clamping pressure against the under surface of the ball or head 6 of the rails and against the upper surfaces of the bases 8 also applying lateral pressure to the rails owing to the inclined surfaces of the plates and portions of the rails which are engaged.

The clamping plate 1 has a hook shaped extension 11 formed thereon intermediate its ends which extension or rib 11 has its lower end formed integrally with the hook shaped extension 12 formed along a portion of the outer edge of the base 7 of the clamping plate 1. The extension 12 has its free edge curved upwardly as clearly shown in Figs. 4 and 6 of the drawing for receiving therein the rounded free end or ball 13 of a clamping pawl 14. The clamping pawl 14 has its upper surface convexly curved for engagement against the under surface of the bases 8 of the rails 4 at their meeting ends and a bolt 15 is connected to the pawl 14 and extends upwardly between spaced ribs 16 and 17 formed on the outer end of an extension 18. The extension 18 is formed upon the clamping plate 2 and its base 7 is enlarged laterally as shown at 19 intermediate its ends to provide reinforcement for the ribs 16 and 17. The bolt 15 also extends through a clamping washer 20 provided with a bolt receiving opening 21 and with depending tongues 22 and 23, one upon each end, which tongues engage over the outer surfaces of the ribs 16 and 17 to hold the washer 20 in place. When the nut 24, mounted on the upper threaded end of the bolt 15 and in engagement with the upper surface of the washer 20, is tightened upon the bolt 15 the pawl 14 will rock upon its point of engagement with the bases 8 of the rails 4, forcing the rounded end 13 downwardly and the bolt carrying end upwardly until the limit of its pivotal movement is reached owing to failure of yielding movement of the hook shaped extension 12, after which further tightening action of the nut 24 will securely clamp the pawl 14 in engagement with the bases 8 applying pressure to the bases from below and also applying pressure to the bases from above owing to the engagement between the rounded end 13 and extension 12 and the pressure of the bolt 15 and nut 24 upon the ribs 16 and 17.

It is, of course, to be understood that the invention may be constructed in various

other manners and the parts associated in different relations and, therefore, I do not desire to be limited in any manner except as set forth in the claims hereunto appended.

Having thus described my invention what I claim is:

1. In a rail joint, the combination, of rail clamping plates, a hook extension on one of said plates, a clamping pawl adapted to engage said extension, and means carried by the other clamping plate and connected to said pawl to adjust the pawl for applying clamping pressure to rails.

2. In a rail joint, the combination, of rail clamping plates having their upper edges shaped to snugly fit the under surfaces of the head of a T rail, a hook extension on one of said plates, a clamping pawl, adjusting means carried by the other of said clamping plates and connected to said clamping pawl for adjusting the clamping pawl for applying pressure to a rail, said pawl provided with a convex surface adapt-

ed for engagement with the under surface of a rail base.

3. In a rail joint, rail clamping plates having their upper edges shaped for snug fit against the under surface of a rail head, a hook extension on one of said plates, a clamping pawl having one end rounded for engaging in said hook extension, laterally extending ribs formed upon the other of said clamping plates, a bolt extending between said ribs and connected to said pawl, a clamping washer on said bolt, a nut on said bolt for drawing said clamping pawl into clamping engagement with a rail and said hook extension.

4. A rail joint comprising clamping plates, a pawl rocking upon the base of the rails and having a pivotal connection with one plate and an adjustable connection with the other plate.

In testimony whereof I affix my signature.

LOUIS PLESHE.
